UNITED STATES PATENT OFFICE.

JOHN G. SNYDER, OF ALTOONA, PENNSYLVANIA.

METALLIC RAILWAY-TIE.

No. 861,548.

Specification of Letters Patent.

Patented July 30, 1907.

Application filed October 24, 1906. Serial No. 340,302.

To all whom it may concern:

Be it known that I, JOHN G. SNYDER, a citizen of the United States, residing at Altoona, in the county of Blair and State of Pennsylvania, have invented certain new and useful Improvements in Metallic Railway-Ties, of which the following is a specification.

The invention relates to improvements in metal railway ties of that description which are made of sheet metal, and more particularly it relates to the clamping mechanism for securing the rail to the tie.

It has for its object the provision of means whereby the clamp can be readily adjusted to meet the rail after the latter has been positioned and which will securely hold it in place.

15 The invention consists in the novel construction, combination and arrangement of parts, such as will be hereinafter fully described, pointed out in the appended claims, and illustrated in the accompanying drawings.

In the drawings, in which similar reference characters 20 designate corresponding parts, Figure 1 is a perspective view of clamping mechanism embodying the invention, showing the same applied to the end of a tie to hold a section of rail to the same. Fig. 2 is a plan view of the end of the tie shown in Fig. 1. Fig. 3 is a plan view of 25 the end of a tie embodying a modification of the invention. Fig. 4 is a similar view showing another modification. Figs. 5 and 7, respectively, are plan and end views of the clamp shown in Fig. 1. Figs. 6 and 8, respectively, are plan and end views of a clamp adapted 30 to the tie shown in Fig. 3.

The tie is of sheet metal and in its formation may be of any construction suitable in the premises. In the present instance it consists of the flat crown or top 1 and the sides 2 spreading apart slightly at their lower edges. 35 These sides entering the material of the road-bed hold the tie against displacement. The usual rail is secured on the crown of the tie by the clamps 3 on opposite sides of the rail and adjustably mounted on the tie. As both clamps are alike, a description of one will suffice for 40 both.

Referring to Figs 1, 2, 5 and 7, which show the preferred embodiment of the invention, the inner end of the clamp is shaped to fit the base and web of the rail and to abut the crown of the same. In the outer end of 45 the clamp, which is flat and rests on the crown of the rail, is the groove 4 extending obliquely across the same. When the clamp is in place the bolt 5, mounted in the tie, passes through the groove 4. In the tie is the opening 6 to receive the head of the bolt, and leading from 50 the opening 6 into the slot 7 into which the shank of the bolt is moved so that the head projects under the adjacent edges of the tie and holds the bolt in place. A nut on the upper end of the bolt serves to secure the clamp to the tie.

55 At the outer end of the clamp is the downwardly projecting flange 8 parallel with the groove 4. This flange

engages the slot 9 in the crown of the tie, which slot is also parallel with the groove 4 when the clamp is in place. The engagement of the flange with the slot serves to hold the clamp against the thrust of the rail. 60 As the flange is shorter than the slot it can be moved endwise therein, which will permit an oblique movement of the clamp on the tie. By means of this oblique movement the clamp can be adjusted to the rail after the latter has been positioned. 65

Projecting from the outer edge of the clamp, at one corner of the same, is the downwardly turned finger 10 to engage the holes 11 in the tie. The holes 11 extend across the crown of the tie in an oblique line parallel to the slot 9. When the finger is in engagement with any 70 one of the holes the clamp will be held against sidewise movement. The intervening spaces between the holes are slight so that a very close adjustment of the clamp to the rail can be secured.

When the clamp is in position, its inner end engages 75 the base and web of the rail and abuts against the under side of the crown of the rail. It is held down upon the tie by the bolt 5 and thereby holds the rail to the tie. The engagement of the flange 8 with the slot 9 holds the clamp against the thrust of the rail; and sidewise movement of the clamp is prevented by the engagement of the finger 10 with one of the holes 11. To adjust the clamp, the bolt 5 is loosened and the outer end of the clamp is raised until the finger 10 is free. The clamp, with the flange 8 registering with the slot 9, is moved 80 obliquely across the tie until it reaches the required position relative to the rail. Then the outer end of the clamp is depressed to lie flat on the top of the tie and the finger 10 engages one of the holes 11. The bolt 5 is then tightened, and the clamp secured in place. 90

In the modification shown in Figs. 3, 6 and 8, the tie and clamp have substantially the same structure, except that in the tie the holes 11^a are recesses leading from the slot 9^a; and also the opening 6^a for the bolt head opens into the slot 9^a. In the modification the 95 finger 10^a extends from the face of the flange 8^a and projects horizontally into the recesses 11^a when the clamp is in place.

In the modification shown in Fig. 4 the openings 11^b are inside of the slot 9^b, instead of outside as in the first 100 instance. The clamp, it is obvious, can be readily shaped to fit the openings 11^b and the slot 9^b.

Having thus described my invention, what I claim and desire to secure by Letters Patent is:

1. In a rail fastener, a tie provided with a series of openings extending obliquely across its crown, a clamp to engage the rail movable diagonally across the crown of the tie, a finger on said clamp to register with said openings, and means for securing the clamp to the tie. 105
2. In a rail fastener, a tie having a slot extending obliquely across its crown and provided with a series of openings extending across its crown in a line parallel with said slot, a clamp to engage the rail, a flange on said clamp to engage said slot and movable endwise therein, a 110

finger on said clamp to register with said openings, and means for securing said clamp to the tie.

3. In a rail fastener, a tie having a slot extending obliquely across its crown and provided with a series of openings extending across its crown in a line parallel with said slot, a clamp to engage the rail and provided with a groove extending obliquely across the same parallel to said slot in the tie when the clamp is in place, a bolt mounted in said tie and projecting through said groove in

the clamp, a flange on said clamp to engage said slot in the tie and movable endwise therein, and a finger on said clamp to register with said openings in the tie.

In testimony whereof I affix my signature in presence of two witnesses.

JOHN G. SNYDER.
